W. G. THOMAS

BABBITTING AND BRASSING MACHINE

Filed March 8, 1922

Inventor

William G. Thomas

By *Grace C. Thomas*

Attorney

UNITED STATES PATENT OFFICE.

WILLIAM GILES THOMAS, OF VICTORIA, VIRGINIA.

BABBITTING AND BRASSING MACHINE.

Application filed March 8, 1922. Serial No. 542,187.

To all whom it may concern:

Be it known that I, WILLIAM G. THOMAS, a citizen of the United States, residing at Victoria, in the county of Lunenburg, State 5 of Virginia, have invented certain new and useful Improvements in Babbitting and Brassing Machines; and I do hereby declare the following to be a full, clear, and exact description of the invention, such as 10 will enable others skilled in the art to which it appertains to make and use the same.

This invention relates to new and useful improvements in machines for babbitting and brassing gibs or keys of the cross-head 15 slides of locomotive pitmen or the like.

One object of the invention is to provide a novel and improved device by means of which a cross-head gib or key can be lined with Babbitt-metal or brass to the thickness desired, and without the ultimate necessity of planing any rough or jagged edges.

Another object is to provide a device of this character by means of which the babbitt 25 or brass, which lines the side walls of the cross-head gib, may be made of a different thickness from that in the bottom wall of the channel or groove.

A further object is to provide a supporting frame for the gib, and a clamp for holding the gib, and babbitt retaining means while the babbitt or brass is being poured 30 into the channel of the gib.

Other objects and advantages will be apparent from the following description when taken in connection with the accompanying drawing.

In the drawings:

Figure 1 is a side elevation of a babbitting 40 or brassing machine made in accordance with my invention, in proper position ready for the reception of the molten babbitting or brassing metal.

Figure 2 is a top plan view of the same. 45 Figure 3 is a vertical transverse center sectional view on the line 3—3 of Figure 2.

Figure 4 is a vertical longitudinal center sectional view on the line 4—4 of Figure 2.

Referring particularly to the accompanying drawing, there is shown a supporting 50 frame which consists of a pair of elongated metal plates 10, disposed on their longer edges and arranged in parallel relation, with transverse bolts 11 disposed through the 55 end portions thereof and having nuts 12 thereon engaged with the opposite side faces

of the plates. The plates are thus held in proper spaced relation. In the upper edge of each of the plates, and adjacent one end thereof, there is formed a pair of notches 13, 60 and in the upper edge adjacent the other end there is formed a single notch 14. In the lower edge of each of the plates below the notches 13, are notches 15, the same being arranged however in staggered relation 65 to the notches 13. A single notch 16 is formed in the lower edge of each of the plates below and offset from the notches 14.

The back of the cross-head gib 17 is formed with a longitudinal central rib 18, 70 which is arranged to lie between the upper portions of the plates 10 and the remaining portion of the back of the gib to rest on the upper edges of the plates 10. Sometimes, in removing the gib from the cross-head the ends thereof will become slightly battered and thus result in the edges at the 75 end of the gib turning down to a slight degree. When the gib is disposed on the plates 10, this down-turned battered portion would rest on the upper edges of the plates 80 and thus prevent the gib from lying level. It is with this in view that the notches 13, 14, 15 and 16 are provided, the downturned battered ends of the gib passing into the 85 notches so that the gib will rest flatly on the upper edges of the plates 10.

A pair of metal blocks 19 are placed transversely of the frame so that they rest on the upper edges of the plates 10 and 90 against the end faces of the gib, said blocks being of a proper depth or thickness to rise above the upper face of the bottom wall of the channel of the gib. A pair of transverse bars 20 of slightly greater length than 95 the blocks 19 are disposed transversely of the frame, on the upper edges of the plates 10 and outwardly of the blocks 19. The ends of the bars 20 are provided with openings through which are disposed the threaded 100 ends of the rods 21, nuts 22 being engaged on the ends of the rods outwardly of the bars 20. One of the bars 20 bears against the outer vertical face of one of the blocks 19, and threaded through the center of the 105 other bar 20 is a clamping screw 23, which bears against the adjacent vertical face of the other block 19, and has on its other end a crank handle 24, by means of which it may be rotated, for the purpose of clamping the 110 blocks 19 firmly against the ends of the gib.

A pair of wedge blocks 25, are placed on

the upper faces of the blocks 19 over the channel of the gib, the upper faces of the wedge blocks being graduated so that they may be moved longitudinally with respect 5 to each other, to move their outer edges toward and away from the side walls of the channel of the gib. The spaces between the outer faces of the wedge blocks and the inner faces of the side walls of the gib will be 10 the thickness of the lining of babbitt or brass of the side walls. It will be noted that the end portions of the blocks 25 rest on the blocks 19, and are thus held elevated above the bottom wall of the channel of the 15 gib. This distance or space representing the thickness the babbitt or brass will be on the bottom of the gib channel.

When the wedge blocks 25 have been properly placed in the gib, the operator 20 pours the molten Babbitt-metal or brass between the side walls of the gib and the wedge blocks, this metal running down into the channel of the gib beneath the wedge blocks and to the blocks 19, which blocks 19 25 act as end walls for the Babbitt or brass lining. Should the operator desire a thicker Babbitt or brass lining in the bottom of the gib, additional plates 26 are placed on top of the blocks 19, so that the end walls of the 30 Babbitt or brass will be permitted to rise to a greater height above the bottom wall of the channel of the gib.

Each of the blocks 25 is provided with a handle 27, to permit the same to be lifted 35 into and out of the gib. When the metal has set or cooled, and it is desired to remove the wedge blocks 25, the upstanding lugs 28, formed on the upper faces of the wedge blocks 25, are struck with a hammer or other 40 tool to drive either one of the wedges longitudinally of the other. The wedges may then be easily lifted out.

The rods 21 permit adjustment so as to accommodate gibs of different lengths.

What is claimed is.

1. A machine for molding Babbitt linings in channel members cross-head gibs comprising a frame for supporting a channel member, the frame having notches for reception of the battered ends of a channel member, transverse blocks disposed on the frame and against the ends of the channel member to prevent escape of the molten Babbitt-metal, a frame including a pair of transverse end bars supported on the frame 55 with one of the bars against one of the blocks, tie members adjustably connecting corresponding ends of the bars, a clamping screw engaged through the other of the transverse bars and bearing against the 60 other transverse block to maintain the latter in position against the end of the gib, and a core comprising a pair of longitudinally adjustable and graduated wedge blocks disposed in spaced relation to the 65 sides of the channel member and supported on the transverse blocks in spaced relation to the bottom wall of the channel member.

2. In a Babbitt lining machine, a frame including parallel spaced side members for 70 supporting a cross-head gib, core supporting means on the side members adapted to close the ends of a gib, and a core comprising a pair of wedge blocks having their oblique faces disposed in slidable contact 75 and each having graduations on its upper face adjacent its oblique face for cooperation with the graduations of the other block, a vertically disposed handle on each of the blocks, and a vertical lug on each block for 80 striking engagement by a hammer to separate the blocks.

In testimony whereof, I affix my signature, in the presence of two witnesses.

WILLIAM GILES THOMAS.
